U.S. Appl. No. 29/392,753, filed May 26, 2011.

Primary Examiner — Eric Goodman

(74) *Attorney, Agent, or Firm* — Womble Carlyle Sandridge & Rice LLP

(57) **CLAIM**

The ornamental design for a modular building, as shown and described.

DESCRIPTION

The specification and drawings of U.S. Design patent application Ser. No. 29/392,753 are incorporated herein in their entirety by this reference.

FIG. 1 is a perspective view of a modular building showing my new design.

FIG. 2 is a front view of the modular building of FIG. 1.

FIG. 3 is a rear view of the modular building of FIG. 1.

FIG. 4 is a left side view of the modular building of FIG. 1.

FIG. 5 is a right side view of the modular building of FIG. 1.

FIG. 6 is a top view of the modular building of FIG. 1; and,

FIG. 7 is a bottom view of the modular building of FIG. 1.

The broken lines shown herein are for illustrative purposes and form no part of the claimed design.
